Patented Oct. 12, 1915.

UNITED STATES PATENT OFFICE.

BENJAMIN DAY CHAMBERLIN, OF CORNING, NEW YORK, ASSIGNOR TO EMPIRE
MACHINE COMPANY, OF PORTLAND, MAINE, A CORPORATION OF MAINE.

GLASS-BLOWING MOLD.

1,156,756.

Specification of Letters Patent. Patented Oct. 12, 1915.

Application filed May 31, 1912. Serial No. 700,831.

To all whom it may concern:

Be it known that I, BENJAMIN D. CHAMBERLIN, a citizen of the United States of America, and a resident of Corning, New York, have invented certain new and useful Improvements in Glass-Blowing Molds, of which the following is a specification.

This invention relates to the construction of molds for blowing fine glass articles.

The molds heretofore employed for this purpose have consisted of a separable iron body, the inside of which is hard coated with carbon formed thereon by the burning off of a hydro-carbon fluid. These molds require to be wetted between each blow, and difficulty is experienced both in maintaining the carbon deposit and from the fact that the molds due to their high conductivity cause the rapid cooling of the article and the consequent formation of stresses therein. These iron molds warp, due to the repeated heating and cooling in use, and then in baking the hard coat and hence lose their ability to produce the higher grade glass article. I propose to avoid these defects by making the mold of a body of low heat conducting material, preferably some agglutinated form of carbon, worked into shape, and inasmuch as such material is not of such inherent strength as to withstand the stresses to which it is subjected, I inclose it in a supporting shell of metal, leaving between the carbon and the shell, a chamber through which water can be circulated, to cool the carbon mold. Thus the carbon of the mold is cooled both upon its interior walls and upon its exterior walls when dipped in the water bath between the molding operations. My invention further consists in the construction, combination and arrangement of the several parts of which it is composed as will be hereinafter more fully described and claimed.

Referring to the accompanying drawings in which corresponding parts are designated by corresponding marks of reference:—Figure 1 is a side elevation of a mold constructed in accordance with this invention. Fig. 2 is a vertical diametrical section taken on line x^2-x^2 of Fig. 1.

As shown my improved mold comprises a two part shell, 1 and 3, adapted to be supported in a suitable mold frame by which such parts may be cooled together and

dipped into the bath, as is usual. Each of the separable parts 1 and 3, as shown, comprise the body casting 1^a and 3^a and the half bottom casting 2^b and 3^b, respectively. The body castings are provided with internally restricted collars 1^c and 3^c and the body castings and the half bottoms together form grooves 1^d and 3^d. It is obvious however that this particular construction of shell may be changed.

The mold proper is of some low heat conducting material, such as lava, soapstone, carbon, etc., preferably of the latter and comprises the two parts 2 and 4 which together constitute and form the mold cavity. Each part 2 and 4 comprise the body parts 2^a and 4^a and the half bottom part 2^b and 4^b, the bottom and body part having flanges 2^c and 4^c thereon held within the grooves 1^d and 3^d of the mold shell, while the body parts 2 and 4 have their upper ends adapted to fit within the restricted collars 1^c and 3^c of the body parts of the mold shell. While I have described each mold half as made in two parts it is obvious that each part may be made in a single piece or any other number of pieces.

It will be noted that the inner carbon-mold-sections are supported by the outer inclosing shell which abuts upon the inner section in a continuous zone near the top and bottom of the inner section.

The mold parts proper are formed of an agglutinated carbon either molded directly into the desired shape or worked out of a block of proper size and are in the form of a comparatively thin wall structure which however is self supporting in that the carbon thereof maintains its shape without breaking. The shell which has been described merely serves for the manipulation of the carbon parts of the mold and to protect them against injury.

The external diameter of the carbon part of the mold is less than the internal diameter of the supporting shell, except at the restricted collars 1^c and 3^c and grooves 1^d and 3^d whereby an annular space 5 encircles the carbon between it and the shell. A corresponding space is left between the carbon bottom of the mold and the bottom of the shell. The shell has apertures 6 formed in its walls communicating with the annular space 5, whereby when the complete mold is

dipped into the water bath not only will the water be in contact with the inner walls of the carbon mold but will also flow around the outer wall thereof and in the annular space, whereby the mold will be effectually wetted and cooled on both sides. This is of importance in maintaining a proper temperature and a uniform heat distribution in the mold and preventing the cracking of the latter due to heat strains. The ability to cool both the exterior and interior of the carbon shell is of great value in permitting the exact regulation of the cooling thereof, without over-cooling. It is obvious that the thickness of the carbon may be varied to suit the varying conditions in the article blown.

With a mold having the carbon wall, it is unnecessary to apply the "hard coat." It is only necessary with such molds to apply the "soft coat," which may be done by applying a coat of oil to the interior of the carbon mold and dusting it over with charcoal or some other suitable form of carbonaceous material, this being before the mold is started in use and not requiring any preliminary baking.

Having thus described my invention what I claim is:

30. 1. In a device of the character described, the combination with an outer supporting shell, of an inner mold section formed of low heat conducting material, the outer shell being separated from the mold section by an intervening space in communication with the exterior of the shell.
2. In a device of the character described, the combination with an outer supporting shell, of an inner mold section formed of carbon material, the outer shell being separated from the mold section by an intervening

space in communication with the exterior of the shell.

3. In a device of the character described, the combination with an outer supporting shell, of a carbon mold section contained therein and spaced therefrom, the shell having apertures communicating from its exterior to the spacing between the mold section and the shell.

4. In a device of the character described, the combination with an inner mold section formed of carbon material and forming an inclosed mold cavity, of an outer supporting shell substantially inclosing the inner mold section, the outer shell abutting upon and supporting the inner section in continuous zones near the top and bottom of such section, and being separated from the inner mold section at other points by an intervening space in communication with the exterior of the shell.

5. In a device of the character described, the combination with an inner mold section formed of carbon material and forming an inclosed mold cavity, of an outer supporting shell surrounding the inner mold section on its sides and bottom, the outer shell abutting upon and supporting the inner section in a zone adjacent to the top of the inner section, and in a zone adjacent to the bottom of the inner section, intervening spaces being formed between the inner mold section and the outer shell at other points, in communication with the exterior of the shell.

In testimony whereof I have signed my name in the presence of two witnesses.

BENJAMIN DAY CHAMBERLIN.
